UNITED STATES PATENT OFFICE

LEON M. SCHOONMAKER, OF FOREST HILLS, NEW YORK

SEWING MACHINE

Application filed August 20, 1926. Serial No. 130,395.

My invention relates to sewing machines, and my primary object is to provide an electric sewing machine so small and compact that it can be carried in a traveler's luggage and used in other situations where the present day "portable" machines are too large, heavy and expensive. Various features of my invention may be employed however in larger sewing machines and certain features even in machines not power-driven.

The accompanying drawings illustrate my invention in both lock-stitch and chain-stitch machines. Fig. 1 is an elevation partly in section of a lock-stitch machine embodying my invention. Fig. 2 is an elevation of the left hand end of the same machine, also partly in section. Fig. 3 is a plan view, a part of the cloth plate being omitted. Fig. 4 is a section adjacent the right-hand end and Fig. 5 is a mid-section. Fig. 6 is a plan view of the left end of the base of the machine with the cloth plate removed. Figs. 7, 8, 9 and 10 are details of the feed mechanism. Fig. 11 illustrates how the machine may be packed in a small box or carrying case. Fig. 12 is an elevation partly in section of a chain-stitch machine embodying my invention. Fig. 13 is a plan view of the machine of Fig. 12. Fig. 14 is an elevation of the left end of the same machine, the cover plate of the head and a part of the cloth plate and presser foot bar being broken away. Fig. 15 is a horizontal section near the center line of the motor. And Figs. 16, 17, 18, 19 and 20 illustrate details of and parts adjacent the feed mechanism of the machine of Fig. 12.

The electric motor and the parts forming the sewing machine proper are built together as a single unit, in contradistinction to the more usual practice which, in effect, is constructing substantially a complete sewing machine and applying thereto a motor constituting more or less an independent unit. As illustrated, the motor itself forms the base and base casing of the sewing machine, the motor mechanism per se being located immediately below the level of the cloth plate, this not only promoting compactness and light weight but also producing a low

center of gravity, which is especially important in miniature machines. This matter is also the subject of a prior copending application of mine, Serial No. 737,484, filed September 13, 1924; the present drawings however illustrate an improvement on the machine described in my prior application, among other things to the ends of lowering the cloth plate and reducing the weight and number of parts.

In portable machines, the bottom of the sewing machine is made flat, whereby it can be set on a table for use. To reduce the height of the cloth plate above this bottom (and elsewhere where compactness is a desideratum), the motor is preferably of a kind in which the field windings are concentrated or located entirely at one or both sides of the armature rather than above or below the armature, and further, of a kind in which the pole pieces, rather than field core yokes, are located above and below the armature. Thus in the motor illustrated it will be observed (Fig. 5) that the pole pieces are above and below the armature while the yokes, two in number, are located at the two sides and the field winding is divided between the two vertical legs of the yokes. This field core outline and armature relation is sometimes referred to as the "Manchester" type of dynamo. By dividing the field winding into two coils 9 located at both sides of the armature rather than concentrating it at one side only, the vertical dimension of each horizontal leg of the yokes is but one-half of what it would be were the field winding concentrated entirely at one side of the armature (same number of flux lines assumed). Furthermore, by such a construction the vertical dimension of the core iron directly above and below the armature shaft may be almost nothing, since there is very little or almost no flux in the horizontal direction at this point; I contemplate that the core iron might even be opened at this point. I prefer a motor embodying these features of construction since thereby the height of the motor may be brought down to but little if any more than the diameter of the armature. Furthermore, such a motor is preferable in machines where, like those il-

lustrated, the motor shaft lies substantially underneath the overhanging arm of the sewing mechanism since this construction places the center of gravity of the motor in or near the vertical central plane of the machine; this is especially important I believe in very small machines.

The group of laminations constituting field core 10 are set into a slot in the bottom plate 11 of the casing of the motor, while the top and two long sides of the motor casing are composed of two flanged pieces 13 and an inset or filler piece 14, the horizontal flanges of the pieces 13 reaching inwardly to an upward projection 15 from the core structure so that the upper part of the core is also confined within a recess in the casing. The inset or filler 14 completes the top closure beyond the left end of the field core structure as shown in Fig. 6; the space to the right of the field core is covered by the head upright or standard 16. Right and left end members 17 and 18 are secured to and secure the bottom and side plates in a suitable manner. Various of these top, bottom, side and end members may be united into integral pieces as constructional convenience may dictate; thus in Figs. 1 to 6 various top and side pieces are joined and in Figs. 12, 14 and 15 two sides, the top and one end are joined into a single piece. The member 12 is a sheet or pad of felt, rubber, or other suitable material attached to the bottom of the machine to prevent marring, reduce noise, etc. The motor shaft 23 is carried in bearings 24 and 25 in the end plates 17 and 18, respectively; these bearings may be of any suitable kind, anti-friction or otherwise. The motor armature 26 and commutator 27 are mounted on the shaft 23 of course; the brushes 28, bearing on the commutator, are carried in bosses 29 projecting from the side members 13. The internal electrical connections have been omitted from the drawings for clarity and in order to emphasize the illustration of more essential parts, but will be understood; the outlet lead 30 from the machine can come out from the back of the upright or standard 16 conveniently, as shown in Figs. 3, 4, 13 and 14.

The head upright or standard 16 rises directly from the top of the motor as will be understood from the foregoing, and may be integral with or bolted to suitable parts of the motor, such as the side plates 13 as before indicated; the former arrangement is employed in the machine of Fig. 12 and the latter in the machine of Fig. 1. The overhanging arm 34 terminates in a head 35, as usual, and preferably the needle bar is shaft-driven by means of a belt 35 reaching between the pulley 36 (or 125) on the upper shaft 37 and a pulley 38 (or 124) on the motor or lower machine shaft 23; the belts illustrated comprise many lines of a light, strong

twine laid parallel and held together as a unit by wire clips in a known manner. I prefer a belt drive from the motor shaft to the top of the standard or upright since this readily provides useful space within the standard, as illustrated by the preferred location of the motor controlling rheostat 39 therein. This rheostat comprises a number of insulating members (four are illustrated) wound with suitable resistance wire, through which and a metal rheostat arm 40 the current is led in such a manner that movement of the rheostat arm 40 over the upper ends of the coils reduces or increases the effective resistance of the rheostat accordingly as the arm is moved, thereby controlling the speed of the motor. The metal arm 40 is carried by the arcuate insulating member 41 journaled on the outside of the bearing 24 (see Figs. 1, 4, 12 and 15) which supports one end of the motor shaft 23; the arcuate member projects through the upper side of the motor casing to the right of the standard 16 within easy reach of the operator's hand. Shoulders 42 to limit the throw of the arcuate member 41 are formed on the end member 17 at opposite sides to the bearing 24.

The needle bars are shown at 46 and carry ordinary needles 47 in a well known manner. Preferably the needle bars 46 are square in cross section to prevent turning and they pass through both the upper wall 48 and lower wall 49 of the heads so as to have adequate bearing. According to my invention, the needle bar is reciprocated by the upper shaft 37 through the agency of a crank pin 50 fitted at or provided with an anti-friction roller on its outer end to travel in a rectangular slot in the cross member 51 which is fastened to the needle bar 46 at right angles to the latter. The crank pin 50 may be located near the outer margin of a complete disk 52 (Fig. 2), or the disk may be cut away to a crank or arranged as a counterweight as indicated in Fig. 14 for example. As the shaft 37 rotates it is apparent that the crank pin 50 will cause the needle bar to make one complete up and down reciprocation with each rotation of the shaft. The presser-foot bar 65 may be placed to the left of the cross member 51 see Figs. 1, 2 and 14). I prefer this type of mechanism for operating the needle bar in preference to the Pittman type, etc. now commonly used, since the illustrated type permits the head being made smaller.

Referring now more particularly to the machine of Figs. 1 to 10: It will be observed that the needle bar 46 is located between the shaft 37 and the operator; the purpose of this is explained later. A take-up lever 53 is hinged at 55 in the machine head directly above shaft 37 and is operated from the same crank pin 50 as drives the needle bar, and for this purpose the pin 50 is mounted in the disk 52 so as to be able to oscillate and is

pierced to receive with a sliding fit the arm 54 which is attached to the take-up lever. Each rotation of the shaft 37 therefore oscillates the arm 54 and take-up 53 through one 5 complete cycle. With both the needle bar 46 and the oscillating end of the take-up lever 53 between the axial line of shaft 37 and the operator, and the shaft 37 rotating in the customary direction (clockwise in Fig. 2), the 10 take-up begins to move down as the needle-bar approaches its mid-position descent, moving slowly at first but with increasing speed as the needle bar descends farther and reaching its maximum speed as the needle bar reaches 15 its lowest point. Because of the relation of the various parts, it will be observed that the take-up continues to fall for a time after the needle starts upwardly. The take-up fully releases the tread therefore at the time the 20 loop is being drawn. Shortly after the needle bar passes its mid-position in its ascent however, the take-up begins to rise, and (because the pin 50 is now nearer the hinge-point 55 than before) rises rapidly. With the 25 parts related as illustrated the entire upward movement of the take-up is accomplished in about one-fourth of a rotation of the shaft 37. The take-up puts the tension on the thread therefore to complete the stitch 30 promptly on the releasing of the loop. In general, the relation between the downward speed of the take-up and its upward speed is a function of the vertical distance between the hinge-point 55 and the axis of shaft 37, 35 and the timing of the needle-bar with respect to the movement of the take-up is a function of the horizontal relation between the axis of the shaft 37 and the axis of the needle-bar. The spool-holder with spool is shown at 58, 40 and in threading up the machine the thread is passed first to the right to a hook 59, thence to the left to a hook 60, downward to the tension 61 and through the eye of the slack thread controller 62, through the eye of the take-up 45 53, and thence to the hook on the lower end of the needle bar 46 and the eye of the needle. The tension device 61 is of a well known type in which the thread passes between circular plates pressed together by a spring under adjustable tension; the slack thread controller 50 62 is likewise a well known form made of spring wire. One end of a band 63 of spring metal, passing around the base of the tension device, provides a stop for the downward 55 movement of the controller 62 as will be understood from Figs. 1 and 2; the spring tension of the band 63 holds it in position on the standard while the position of the stop can be adjusted by sliding the band 63 around 60 the standard to an appropriate place. The presser foot 64 is mounted as usual on a presser foot bar 65 which, however, is also square preferably to prevent turning in its support. Preferably the bar 65 itself passes 65 through only the lower wall 49 of the head while its upper end is guided and its tension is applied by bolt 66 and plug 68. The bolt 66 is provided with a knurled head 67 and threaded at its lower end, and is held in the upper head 48 by a circumferential slot in the bolt 66 and a pin or the like in the head which locks the bolt in the head wall but permits it to be turned. The threaded end of this bolt enters corresponding threads in the square or feathered plug 68, over which the 70 presser foot bar 65 slides easily. Between the lower end of the plug and the presser foot bar 65 is located a spring 69. The plug therefore acts as a guide, and the tension of the foot is adjustable by turning the bolt 66. 75 For machines where compactness is essential, I prefer this mounting for the presser foot 64, rather than the mounting in which the presser foot adjusting screw rises as the pressure of the presser foot is reduced, since 80 relieving the pressure of the foot on the cloth does not increase the over-all dimensions of the machine. The presser foot is lifted when desired by means of the usual cam lever 70 engaging underneath a projection from 85 the presser foot bar 65 as appears in Figs. 1 and 2.

As mentioned before, the machine of Figs. 1 to 10 is a lock stitch machine. The bobbin 76 is carried within a rotary looper 77, being 90 releasably held therein by the pivoted lever 78. The looper is of the type which operates with a constant speed of rotation, and the looper end bobbin, illustrated need not be described further; they will be recognized to 95 be of a well known type in which the looper makes two rotations for each reciprocation of the needle; and at each reciprocation draws a loop of the needle thread around the bobbin. I mount the looper directly on the 100 motor-shaft 23 and to accommodate the two rotations of the looper for each reciprocation of the needle 47, I make the pulley 38 half the size of the upper pulley 36 so that the upper shaft 37 is driven at half the speed of the 105 lower or motor shaft 23.

The feed is of the four-motion type and is operated by the motor shaft 23; speed reducing gearing is interposed in the machine of Figs. 1 to 10 since in this machine the motor 110 shaft makes two rotations for each needle reciprocation. The feed dogs 82 are bolted at 83 to an irregularly-shaped frame 84 (Fig. 10) as appears in Figs. 2 and 6. The end of the frame toward the operator comprises a 115 pair of ways 85 to slide on an oscillating block 86 pinned on the motor end wall 18; a groove in one end of the slide-ways 85 as indicated, receives a corresponding flange on the block 86 which thus tends to hold the 120 member 84 to the face of the plate 18. At the opposite end of the frame 84 are a pair of vertical wall members 87 and a pair of horizontal wall members 88 forming a compound 125 yoke for receiving respectively the cams or 130

eccentrics 90 and 91 which are angularly displaced 90° from each other. The eccentric 91 which produces the up and down motion, is fixed on the hollow stub shaft 92; the eccentric 90 however, which determines the length of the stitch, is slotted (see Figs. 7 and 9) in such a direction that its eccentricity may be increased or diminished by sliding the eccentric transversely of the shaft. To control the position of the eccentric 90 on the shaft 92, a sliding sleeve 93 is inserted in the hollow shaft and externally provided with two pins 94 which project through axially-extending slots 95 in the shaft walls and into inclined slots 96 in the cam 90 (see broken lines in Fig. 7); internal screw-threads in the sleeve 93 and external threads on the bolt 97, turning loosely in the left end of the stub shaft 92 but grooved and pinned in the shaft to prevent longitudinal movement, permit the sleeve 93 to be moved to the right or to the left and thereby the eccentricity of the eccentric 90 changed as desired and accordingly the length of the stitch changed as desired. A knurled head 98 on the pin 97 permits the adjustment to be made by hand. The stub shaft 92 is driven by gears 99 and 100, the latter being half the size of the former and mounted on the motor shaft 23 while the former is mounted on the stub shaft. It will be apparent from the construction that the eccentric 91 will raise and depress the frame 84 and thereby the feed dogs 82 on the frame, and the eccentric 90 will reciprocate the frame and dogs back and forth, once for each two rotations of the motor shaft and hence once for each reciprocation of the needle. By a proper angular relation of the two eccentrics to each other the dogs will be drawn away from the operator while raised, and by a proper angular relation of the eccentrics to the shaft 23 the cloth will be advanced while the needle is raised. One end of the stub shaft 92 has a bearing in the end wall 18; a bracket 101 extended from the top of this end wall supports the other end of the stub shaft and also provides a hook 102 to maintain a part of the bobbin-looper combination 76-77 stationary as will be understood. Especially in very small machines it is desirable that the cloth plate 106 be larger than the base of the machine. In order to reduce the over-all dimensions of the machine for packing purposes therefore, I make the cloth plate 106 detachable, along with or without the throat plate 107 in the region of the feed dogs 82 as desired. Underneath the plate on one side of the machine, is provided a hook 108 (Figs. 2 and 5) arranged to enter a recess in the adjacent side plate 13; on the opposite side of the machine a releasable latch, hook or eccentric 109 is provided with a finger piece 110 whereby this hook can be engaged in a recess in the adjacent side plate 13 and the cloth plate thereby located in position for

use. By releasing the hook 109 the plate 106 can be lifted up and removed, the presser foot first being raised to permit the cloth plate being passed underneath. Fig. 11 illustrates how a machine with a reasonably large detachable cloth plate can be packed for storage or transportation. The case 113, it will be observed, may be made just deep enough to take the machine and only a little wider than the base casing of the machine; a cloth plate of corresponding length and width can then be slipped into the case vertically beside the machine. The cover 114 of the case may be equipped to carry extra bobbin 76, bobbin winder 115, tools 116, etc.

I have applied a lamp to light the work, preferably on the side of the machine nearer the operator. As indicated, the lamp socket 117 is attached to the overhanging arm 34; a pull chain for a switch, if desired, is indicated at 118. A lamp 119 is shown screwed into the socket and an overhanging shade and reflector is shown at 120. I prefer to locate the lamp on the side of the machine nearer the operator in order to fully light the cloth at the point where it passes underneath the presser foot and needle. In machines having a longer overhanging arm, it is possible to find a satisfactory position for the lamp on the side of the arm remote from the operator; with small machines however it is more convenient to locate the lamp on the near side of the arm.

For winding bobbins I provide a bobbin winder such as shown at 115, one end of which is adapted to receive the bobbin while the other end is split (Fig. 1) for entry and frictional engagement in a recess in the end of one of the shafts, such as the right end of the lower shaft 23. It will be understood that the bobbin winder 115 is intended to be inserted when required for use and removed again when the machine is to be packed in its case. Such a winder does not increase the overall packing dimensions of the machine or materially increase the weight. Much of the foregoing description applies to the chain stitch machine of Figs. 12 to 20 as will have been understood. Being a chain stitch machine however, no bobbin is used and the looper 123 is of a correspondingly different type in the machine of Figs. 12 to 20 as will be understood. As before however, the looper is applied directly to the end of the motor shaft 23 but inasmuch as in this type of machine the needle reciprocates with each rotation of the looper, the pulleys 124 and 125 on the motor shaft 23 and the upper shaft 37 are of equal size instead of one being twice the size of the other as in the lock stitch machine, shown in Fig. 1. In the machine of Fig. 12 also, the take-up is the needle bar 46 itself, the thread passing from the tension device through an eye in the upper end of the needle bar and thence downwardly. As the

needle bar reaches its uppermost position, the tension on the thread is released in a very simple manner. The tension device consists as usual of two plates 127 and 128, the first of which is pressed toward the other by a spring 129 held by thumb-nut on the supporting post 130 which is threaded into the side of the overhanging arm 34. The inner end of the post 130 is hollow and contains a sliding 10 pin 132 which reaches to a cam surface 133 on the shaft 37; this surface may be provided by cutting away a part of the shaft as indicated. As the high part of the cam passes the pin, the pin is pushed farther into the post 130 and a connection (reaching through 15 the wall of the post) between the pin and the plate 127, pushes the plate 127 slightly away from the plate 128; as the high part of the cam leaves the pin the spring 129 restores 20 the parts to the initial positions and resumes the tension.

The carrier for the thread spool consists of a bracket 135 fastened to the machine head at the back of the machine, from which depends 25 a rod 136. The spool of thread 137 is pushed up onto this rod from underneath and the collar 138 is slipped onto the rod underneath the spool; the collar is then fastened to the rod by the thumb-nut 139.

30 Inasmuch as the needle in this machine makes a complete reciprocation during each rotation of the looper shaft 23, no speed reducing gearing is required to permit the feed to be driven from the shaft 23. The feed dogs 35 142 are bolted to an irregular frame 143 (Fig. 18) differing in shape but resembling in function and operation the feed frame of Fig. 10. As in the machine of Fig. 1, the feed frame has guide-ways 144 by which it is carried 40 on a block 145 bolted to oscillate on the motor end wall 18, and a pair of vertical walls 146 and a pair of horizontal walls 147 against which operate two eccentrics 148 and 149 respectively. The eccentrics are mounted on 45 the motor shaft 23. The eccentric 149, which gives the up and down motion, is fixed directly to the shaft 23 as indicated in Fig. 15, just to the right of looper 123. To the right of this eccentric 149 is located the eccentric 50 148 which, as in the machine of Fig. 1, is provided with an elongated slot (through which the shaft 23 passes) and inclined slots 150 like the slots 96. The control pins 151 pass through axial slots 152 pierced in the shaft 23, and the latter is made hollow to receive a 55 sliding rod or sleeves 154 to carry the pins 151. Resembling the sleeve 93, this rod 154 is internally threaded and adjusted axially of the shaft by means of the adjustment screw 60 155 which is pinned but rotatable within the shaft 23; as illustrated this screw may be kerfed at its outer end to receive a screw-driver for adjusting the feed. The feed dogs 142 are attached at 141 to the frame 143.

65 It will be understood that while I have

illustrated and described the best forms of my invention of which I am now aware, my invention is not limited to the details illustrated and described except as appears in the claims. Furthermore, I am aware that in certain dynamo-electric machines the armature constitutes the stationary structure and the field or exciting windings rotate; it will be understood therefore that wherever in the claims I mention the looper as mounted on or driven by the armature or armature shaft, or the like, I include thereunder mounting the looper on or driving it by the field or field shaft, and the like, if the field windings constitute the rotating structure, unless the contrary appears.

I claim:

1. A sewing machine comprising an electric motor, connections therefrom for actuating the needle, and a rotary looper mounted on the armature shaft of the electric motor.

2. A multiple thread swing machine comprising an electric motor, connections therefrom for actuating the needle, a rotary looper 85 mounted on the armature shaft, a bobbin adjacent the looper, a cloth feeder, a stub shaft adjacent the looper to actuate said feeder, and means through which the armature shaft turns said stub shaft at reduced speed to actuate the feeder.

3. In a sewing machine having an upright standard rising from the machine base and carrying an overhanging arm supporting the needle mechanism, and mechanism at the machine base cooperating with the needle to complete the stitch, an electric motor at the machine base, extending underneath and immediately below the path for the material to be sewn, to actuate the sewing mechanism, said motor having its armature shaft horizontal and its field winding substantially concentrated horizontally of the armature.

4. In a sewing machine having an upright standard rising from the machine base and carrying an overhanging arm supporting the needle mechanism, and mechanism at the machine base cooperating with the needle to complete the stitch, an electric motor at the machine base immediately below the path of the material to be sewn, to actuate the sewing mechanism, said motor having its armature shaft horizontal and its field winding substantially concentrated into two coils, 110 115 one at each side of the armature.

5. In a sewing machine having an upright standard rising from the machine base and carrying an overhanging arm supporting the needle mechanism, and mechanism at the machine base cooperating with the needle to complete the stitch, an electric motor at the machine base, immediately below the path for the material to be sewn, to actuate the sewing mechanism, said motor having its 125 130

- field winding disposed horizontally of the armature and its pole pieces above and below the armature.
6. The machine of claim 5 characterized by the fact that a rotary looper is mounted on the armature shaft.
7. The machine of claim 5 characterized by the fact that the feed mechanism is driven by the armature shaft.
- 10 8. The machine of claim 5 characterized by the fact that a rotary looper is mounted on the armature shaft and that the armature shaft, at a point adjacent the looper, drives cam mechanism operating the feed.
- 15 9. The sewing machine of claim 5 characterized by the fact that a looper and bobbin are mounted on the armature shaft, and that a lay shaft, driven by the armature shaft through speed reducing gearing, carries two cams operating a four-motion feed dog.
- 20 10. The machine of claim 5 characterized by the fact that a looper is mounted on the armature shaft, and that two cams, one operating a feed dog vertically and the other operating the dog horizontally and being adjustable to vary the horizontal movement of the feed dog, are driven by the armature shaft.
- 30 11. In a sewing machine having needle actuating mechanism, a shaft at the machine base to actuate the looper cooperating with the needle, a parallel shaft, a gear whel on the parallel shaft meshing with a gear wheel on the other shaft through which the parallel 35 shaft is driven, a feeding structure mounted to slide and oscillate, an eccentric cam fixed to the parallel shaft to move said feeding structure vertically, a second eccentric cam mounted on the parallel shaft to move said structure horizontally, said second eccentric cam having a slot through which the parallel shaft passes, and a member within the parallel shaft to adjust said second cam transversely of the parallel shaft to adjust the 40 feed.
- 45 12. In a sewing machine, a base therefor providing a substantially vertical stationary surface, a feeding mechanism comprising a structure, one side of which bears against said surface and having a feed dog at its opposite side, a rotating shaft, an eccentric cam fixed to said shaft to engage and move said structure vertically, a second eccentric cam also mounted on and driven by said shaft to engage and move said structure horizontally, said second cam having a slot through which the shaft passes, and means for moving said second cam transversely of the shaft to adjust the feed.
- 50 60 13. The combination of claim 12 characterized by the fact that the means for moving said second eccentric cam on the shaft comprises a member movable within and lengthwise of the second shaft, a pin on said member passing through a slot in the wall of the
- shaft and engaging an angular slot in the second cam so that moving said member lengthwise of said shaft changes the throw of said second cam.
14. In a sewing machine, a feeding mechanism comprising a structure having means to engage the work, a rotating shaft, an eccentric cam fixed on said shaft to move said structure vertically, a second eccentric cam also mounted on and driven by said shaft to move said structure horizontally, said second cam having a slot through which said shaft passes, a member within and movable lengthwise of the shaft, a pin on said member passing through a slot in the wall of said shaft and into an angular slot in the second cam so that moving said member lengthwise of the shaft changes the throw of said second cam, and a rotatable member fixed within the shaft against movement lengthwise of the shaft and threaded to the member carrying the pin so that turning said rotatable member moves the pin-carrying member lengthwise.
15. In a sewing machine, a needle bar provided with a slot to receive a crank, a shaft provided with a crank to enter the needle bar slot to actuate the needle bar, and a thread take-up, the crank having an oscillatable connection with the shaft and being pierced to receive the thread take-up to actuate the latter.
16. In a sewing machine, a needle bar, a shaft substantially at right angles thereto, the needle bar being provided with a slot substantially at right angles to both the needle bar and the shaft and the shaft having a crank pin engaging in the slot through which the shaft reciprocates the needle bar, and a thread take-up also connected to said crank pin for actuation thereby, the thread take-up member engaging the crank pin being hinged substantially above said shaft and the needle bar being located at one side of the shaft axis.
17. In a sewing machine, a needle bar, a shaft substantially at right angles thereto, the needle bar being located at one side of the shaft axis and being provided with a slot and the shaft having a crank pin, rotatable with respect to the shaft, engaging in the slot for actuating the needle bar, and a thread take-up hinged substantially above the shaft and having a member engaging and slidale with respect to the crank pin.
18. A sewing machine comprising an upright standard and overhanging arm with the needle mechanism, an electric motor at the base of the machine, a connection through which the armature shaft of the electric motor drives the needle mechanism, a second shaft at the base of the machine, substantially parallel to the armature shaft and connected to the armature shaft to be driven thereby, a feed device for the work, means

- for operating said feed device, said means being mounted on one of said shafts, and a looper mechanism driven by the other of said shafts.
5. 19. In a sewing machine, a motor field, a rotating armature, a looper on the armature shaft, another rotating shaft, a needle actuated thereby, and means connecting said shafts through which the second mentioned 10 shaft is operated at a speed different from and proper with respect to the speed of the armature shaft.
20. In a sewing machine, a motor field and a rotating armature at the base of the machine, a rotary looper mounted on the armature shaft, a rotating shaft at the overhanging arm of the machine, a needle bar actuated thereby, and means connecting said shafts through which the needle bar actuating shaft 25 20 is operated at one-half the speed of the looper shaft.
21. In a lock-stitch sewing machine, a shaft at the base of the machine, a motor field structure and a rotating armature on the 25 shaft at the base of the machine, a rotary looper and bobbin mounted on said shaft, the looper rotating with said shaft, a rotating shaft at the overhanging arm of the machine, a needle bar actuated thereby, means connecting said shafts through which the needle bar actuating shaft is actuated at one-half 30 the speed of the looper shaft.
22. In a sewing machine, a rotating shaft at the base of the machine, a motor armature 35 on said shaft, a rotary looper mounted on said shaft, a rotating shaft at the overhanging arm of the machine for actuating the needle bar, means connecting the said shafts through which the needle bar actuating shaft 40 is operated at one-half the speed of the looper shaft, and a second shaft at the base of the machine, for operating the feed, so connected to the first mentioned shaft that the first 45 mentioned shaft is driven at twice the speed of the feed operating shaft.
23. In a sewing machine, a motor field structure, a rotating armature, a looper on the armature shaft, another rotating shaft, a needle actuated thereby, and means connecting said shafts through which the second mentioned shaft is driven from the armature shaft.
24. In a sewing machine having an up- 50 right standard carrying an overhanging arm with the needle mechanism, a looper mechanism at the base of the machine, a structure at the base of the machine movable vertically and horizontally and carrying a feed dog, two parallel rotating shafts at the base of the machine, one driving the looper mechanism and the other carrying two cams engaging said structure, one of said cams reciprocating the structure vertically and the other reciprocating the structure horizontally, one of said 55 60 65 70 75 80 85 90 95 100 105 110 115 120 125 130
- shafts being driven, and means connecting the two shafts through which said driven shaft drives the other.
25. A portable sewing machine adapted to be rested on a table for use, comprising a low substantially-flat-bottomed base, the cloth plate of the machine being immediately at the top of said base, an upright standard rising from said base and carrying an overhanging arm supporting the needle mechanism, mechanism at said base cooperating with the needle to complete the stitch, and an electric motor within said base to actuate the sewing mechanism and comprising a rotating armature, pole pieces above and below the armature, field core yokes at the two sides of the armature, and the field winding surrounding said yokes.
26. In a sewing machine having an upright standard rising from a base and carrying an overhanging arm supporting the needle mechanism, a rotating shaft at the base substantially parallel to said overhanging arm, a feeding mechanism comprising a unitary structure and placed substantially transversely of said shaft, movable both vertically and horizontally, and having means to engage and feed the work, an aperture being provided in said structure into which said shaft extends, a cam on said shaft at said aperture to engage and raise said structure, and a cam on said shaft at said aperture to engage and positively move the structure horizontally in both directions, said latter cam being adjustable on its shaft to change its eccentricity to change the feeding action of said feeding mechanism.
27. In a sewing machine, a yoke carrying a feed dog to engage the cloth and provided with two pairs of faces placed substantially at right angles to each other, a rotating shaft, a feed cam fixed to said shaft, and a second feed cam carried by said shaft and adjustable thereon to change its throw, said cams engaging said two pairs of faces respectively to actuate the yoke.
- In testimony whereof, I have signed this specification.
- LEON M. SCHOONMAKER.
